UNITED STATES PATENT OFFICE

RENÉ LALIQUE, OF PARIS, FRANCE, ASSIGNOR TO LUCIEN LELONG, INC., OF CHICAGO, ILLINOIS, A CORPORATION OF ILLINOIS

DESIGN FOR A BOTTLE OR SIMILAR ARTICLE

Application filed November 16, 1931. Serial No. 41,746. Term of patent 7 years.

To all whom it may concern:

Be it known that I, RENÉ LALIQUE, a citizen of the Republic of France, and a resident of the city of Paris, in the Republic of France, have invented a new, original, and ornamental Design for a Bottle or Similar Article, of which the following is a specification, reference being had to the accompanying drawings, forming a part hereof.

On the drawings:

I claim:

The ornamental design for a bottle, or a similar article, as shown.

RENÉ LALIQUE.
